(57) **CLAIM**

The ornamental design for a knife handle, as shown and
described.

DESCRIPTION

FIG. 1 is a front perspective view of a knife handle showing
our new design, with a blade and blade holder shown in
broken lines;

FIG. 2 is a bottom perspective view thereof;

FIG. 3 is a front elevation view thereof;

FIG. 4 is a rear elevation view thereof;

FIG. 5 is a top plan view thereof; and,

FIG. 6 is a bottom plan view thereof.

The aspects of the knife handle depicted by broken lines
form no part of the claimed design. The broken line show-
ings of the blade and the blade holder are provided for
purposes of environment and form no part of the claimed
design.
